UNITED STATES PATENT OFFICE

2,625,391

METHOD OF ASSEMBLING CONTINUOUS-FORM STATIONERY

Louis Jensen, Chicago, Ill., assignor to Uarco
Incorporated, a corporation of Illinois

Application March 31, 1950, Serial No. 153,221

5 Claims. (CL 270—39)

1

This invention relates to an improved method of assembling continuous-form stationery with one-time carbon, and more particularly to a number of steps performed in timed relation to assemble the parts and form them into a continuous zig-zag folded pack.

Heretofore, stationery of this type was made up by a number of separate operations, and when the parts were brought together considerable hand work was involved. By the present invention, an automatic method is provided which is faster and eliminates more than half of the labor.

Continuous-form stationery usually is printed on cylinder presses and it is convenient to punch marginal feed holes and cross lines of weakening between the forms on the printing press. Carbon paper usually is run directly from the coating machine into a roll. Heretofore, the carbon paper was perforated and provided with feed holes, rerolled, and then taken to a collating machine where it was interleaved with the stationery strips. By means of the present invention, the carbon strips are put under a slight tension, are punched marginally, then provided with cross lines of weakening, and then brought into interleaved aligned relation with the stationery strips by means of feed wheels and folded into packs.

The invention is illustrated diagrammatically in the accompanying drawings, in which—

Figure 1 is a plan view showing how the stationery strips and one-time carbon strips are brought into aligned relationship in the machine; Fig. 2, a longitudinal elevational view of the machine; Fig. 3, an elevational view of the stationery feeding portion of the machine; Fig. 4, a fragmentary diagrammatic view of the drive means for operating the parts in timed relation; and Fig. 5, a perspective view of a folded strip of stationery.

The steps of the present invention are performed, as indicated in Fig. 1, by advancing the one-time carbon strips 6 in one direction and bringing in the stationery strips 7 at an angle from one side, and turning the strips so as to travel in the same direction as the carbon strips. The assembled interleaved strips are then folded automatically to form a flat pack 8.

As shown in Fig. 2, a number of carbon rolls 9 are provided at one end of the machine, and the strips 6 are drawn out by means of power-driven feed rolls 10. The one-time carbon is then drawn through a punching machine 11 which punches the marginal feed holes in the

2

carbon strips. The carbon then advances, assisted by feed rolls 12 to a cross perforating roll 13 which makes a line of weakening across the carbon strips between each form length.

5 The carbon strips are drawn through the angle bar interleaver by means of feed rolls 14 which keep the carbon paper under a slight tension, but not enough to cause separation at the lines of weakening. The strips 6 are then drawn up to the folding machine by means of rolls 15 provided with feed pins 16. The stationery then moves into the folding machine 17 which presses alternate lines of weakening in opposite directions to form the zig-zag pack which, assisted by the pressure flappers 18, forms into a pack on the belt conveyors 19 and 20, and is fed out of the machine.

20 In the diagrammatic view of Fig. 2, only two carbon strips are used, but a number of additional strips may be used in the same way. However, it has been found that not more than two strips should be fed through a pair of feed rolls 12, so that each strip will be engaged by a roller. If more than four one-time carbon strips are needed, additional sets of feed rolls 12 may be provided. The rolls 14 are driven at a slightly faster peripheral speed than the rolls 12 to maintain a light tension. Idler rollers press the strips lightly against the rolls.

25 In Fig. 3 is shown diagrammatically how rolls of punched and cross weakened continuous-form stationery strips 7 may be led from rolls 21. The strips are led under a tensioning roll 22 and over a feeding belt 23 provided with pins 24. The feeding device is driven in timed relation to the units operating on the carbon strips. It is desirable to have the machine set up so that an operator can cross the stationery strips 7 rather than by walking around the end of the 30 stationery side of the machine. Accordingly, a bridge 24 is provided, and the strips 7 are guided underneath the bridge on guide rollers 25 up to rollers 26. They are then led across the path of the carbon strip, are reversed, as indicated at 35 27, and then are turned about angle bars, as indicated at 28, so as to travel forwardly, interleaved by the carbon strips 6. Separate tensioning rolls 29 are provided which are similar to the rolls 14 for the carbon strips. There will be 40 a slight drape in both the carbon strips 6 and the stationery strips 7 between the feed rolls 14 and 29 and the pin feed rolls 15.

45 As shown in Fig. 4, all of the units are driven in timed relation from a main drive shaft 30, on which bevel gears may be provided to drive the

feed rolls 10 for the carbon strips, the punching machine 11, the cross perforating device 13 and the feed rolls 12. The same shaft also drives the feed rolls 29 and 14, and also the feed rolls 15. The folding mechanism 17 and the conveyors 19 and 20 are also driven from the shaft 30, so that all of the parts operate in timed relation. As shown in Figs. 3 and 4, a chain 31 drives a shaft 32 below the bridge 24, and a chain 33 drives a shaft 34, which in turn drives the feeding device 23 by means of a chain 35. Thus the stationery also is advanced in timed relation to the carbon strips.

In operation the strips of carbon are drawn from the rolls 9 and brought into superposed relation, so that they may be punched simultaneously as they advance through the unit 11. The strips are then drawn in pairs by feed rolls 12, and are maintained under a light tension by the rollers 14 as they pass through the cross punching device 13 which provides a line of weakening in each form length in a definite relation to the marginal perforations. The pre-punched stationery is advanced in timed relation by the feeding device 23, and is drawn under the bridge, across the path of the carbon strips, and is turned so as to travel in the same direction as the carbon strips. The stationery is then drawn into juxtaposition and fed into the folding device which provides zigzag folds to form a flat pack 8.

The foregoing detailed description is given for clearness of understanding only, and no unnecessary limitations should be understood therefrom, for some modifications will be obvious to those skilled in the art.

I claim:

1. The method of assembling continuous-form stationery with one-time carbon: advancing strips of carbon from a source of supply into superposed relation; punching regularly spaced feed-holes in a margin of said superposed carbon strips; forming at each form length cross lines of weakening in the superposed carbon strips, at regularly spaced intervals with relation to said feed-hole; separating said advancing carbon strips into paths coincident with the paths of sta-

tionery strips; advancing into interleaved relation with the carbon strips, stationery strips having marginal perforations and cross lines of weakening in each form length corresponding to the perforations and cross lines of weakening in the carbon strips, the advance of said stationery strips being in timed relation to the advance of said carbon strips; bringing said stationery strips and carbon strips into aligned juxtaposition by means of the feed-holes; and zig-zag folding said assembled strips.

2. The method as specified in claim 1, in which the carbon strips and the stationery strips are advanced to interleaved relation in the same direction from different directions relative to each other.

3. The method as specified in claim 1, in which the stationery strips are advanced to interleaved relation with the carbon strips from a direction forming an angle with the direction of advance of the carbon strips, and are then turned to advance in the same direction as the carbon strips.

4. The method as specified in claim 1, in which the assembled strips are zig-zag folded in timed relation to their advance.

5. The method as specified in claim 1, in which the carbon strips are maintained under a substantially uniform light tension while traveling through the punching and cross perforating operations.

LOUIS JENSEN.
